[57] CLAIM

The ornamental design for a portable beverage preparation cabinet, as shown and described.

DESCRIPTION

FIG. 1 is a perspective view of a portable beverage preparation cabinet showing our new design; FIG. 2 is a front elevational view on a reduced scale with respect to FIG. 1 thereof;

FIG. 3 is a top plan view on a reduced scale with respect to FIG. 1 thereof;

FIG. 4 is a rear elevational view on a reduced scale with respect to FIG. 1 thereof;

FIG. 5 is an end elevational view being a mirror image of the side not shown and on a reduced scale with respect to FIG. 1 thereof; and,

FIG. 6 is a bottom plan view on a reduced scale with respect to FIG. 1 thereof.

FIG. 1

FIG. 2

FIG. 3

FIG. 4
